UNITED STATES PATENT OFFICE

JONATHAN P. B. FISKE, OF DETROIT, MICHIGAN, ASSIGNOR, BY MESNE ASSIGNMENTS, TO KELVINATOR CORPORATION, OF DETROIT, MICHIGAN, A CORPORATION OF MICHIGAN

REFRIGERATOR

Application filed March 14, 1921. Serial No. 452,015.

This invention relates to refrigerators and more particularly to mechanical refrigerators of the compression type.

One of the objects of the invention is the provision of a header or expansion tank in the refrigerant system to provide a chamber that is continually only partially filled with liquid refrigerant thus providing ample space above the level of the liquid refrigerant for the same to vaporize so that dry vapor alone is drawn into the compressors from the suction side of the device to thereby materially increase the efficiency of this type of refrigerators.

Another object of the invention is the construction of an automatically operated refrigerator which is provided with an expansion chamber associated with the upper portion of the brine tank for assisting in cooling the same.

Another object of the invention is the construction of a refrigerating system for the preservation of food with improved means associated therewith for also effectively and rapidly freezing water or other substances.

A still further object of the invention is the employment of means for automatically starting and stopping the motor together with an expansion chamber located within the refrigerating chamber and a closure or valve between the refrigerating chamber and the cooling or food compartment, whereby it is necessary for the motor to run only at infrequent intervals.

Other objects and advantages of the invention will appear as the description proceeds.

On the drawings:

Fig. 1 is a vertical section of the refrigerator looking toward the back;

Fig. 2 is a diagrammatic view of the device; Fig. 3 is a top plan view of the closure or valve, parts broken away; and

Fig. 4 is a sectional view on line 4—4 of Fig. 3.

On the drawings, the numeral 1 designates a refrigerator which may be of the usual construction having the heat insulated chamber 2 for the refrigerating unit and having a cooling or food compartment. The food compartment may have any convenient arrangement, as for example, it may consist

of the side compartment 3 and the compartment 4 beneath the chamber 2. The compartments 3 and 4 may together be considered as forming a single L-shaped compartment. If a partition between the compartments 3 and 4 be employed it will, of course, be provided with a ventilating opening for the circulation of air therethrough. As shown, however, no partition is employed.

The chamber 2 has two openings therein, one located above the other for the circulation of air therethrough. One of these openings may be located in the upper portion of the heat insulated side wall or partition 5 as at 8 and the other at a lower level as for example at 6 in the bottom wall 7. The opening 6 is closed by an automatically operated valve 15 which is controlled by means of the thermostat 16. This valve 15 may be of any form and operated by any suitable mechanism which is controlled by the temperature within the cooling chamber 3. As shown, the valve or damper 15 (see Figs. 3 and 4) is secured within the opening 6 by means of brackets 17 which are attached to the walls of the opening. Arms 18 adjustably secured to the brackets 17 are connected to a U-shaped support 19 which in turn supports a corrugated longitudinally extensible member or bellows 20. A head 21 is secured to the upper end of this bellows. The upper portion of the head 21 extends through a plate 22 which is secured by bolts 23 to the U-shaped support 19 as clearly shown in Fig. 1. Links 24 pivoted to lugs carried by the plate 22 cross each other at their inner ends and are pivoted to the head 21 as at 25. The outer ends of these links have slotted connections with the damper member 26 so that when the bellows 20 expands the links 24 will act as lazy tongs to elevate the damper member 26 to permit circulation of air through the opening 6. The damper member 26 has its edges 27 bent downwardly so that it somewhat resembles an inverted dish. The edges 27 of the member 26 engage the top of the wall 7 about the opening 6.

The thermostat 16 consists of the bulb 28

partially filled with a liquid that vaporizes at comparatively low temperatures, as for example, sulphur dioxide (SO_2). A tube 29 connects the bulb 28 with the lower end of the bellows 20. When the temperature in the compartment 3 rises, it causes the liquid sulphur dioxide within the bulb 28 to vaporize, thus increasing the pressure therein, which is communicated to the bellows and extends the same to open the damper or valve 15 to permit cold air from the chamber 2 to pass down into the food compartment to thus lower the temperature therein.

Located within the chamber 2 is what may be termed the refrigerating unit 10. This unit consists of a large expansion tank or header 11, a tube 12 and two series of pipes. The two series are opposite each other and are so arranged that the pipes 13 at one side and the pipes 13' at the other may be said to form a series of loops which are connected to the header in multiple instead of in series. As shown on the drawings, the upper ends of the pipes 13 and 13' are connected to the header 11 and at their lower ends to the tube 12 which extends parallel to the header 11.

The refrigerating unit may be associated with a brine tank 9 suitably supported within the chamber 2. This tank contains brine, as calcium chloride solution in which the expansion pipes are immersed. The calcium chloride solution is poured into the brine tank through an opening which is then closed by a plug 14 which substantially seals the liquid in the tank to prevent evaporation of the brine as well as to prevent its splashing over on moving the refrigerator.

The brine tank is provided with chambers 16 therein which receive drawers or trays 17' that are adapted to contain water or other substances to be chilled or frozen. The loops of the pipes 13, 13' extend down into the brine above, below and on each side of the chambers 16 to thereby maintain the brine at a uniformly low temperature around and about said chambers 16 without the necessity of a mechanical agitator for the brine. If desired, plates 90 and 91 attached to the pipes 13 and 13' respectively extending along from front to back of the tank may be employed to facilitate the circulation of the brine, the colder brine descending on the pipe side of the plates and ascending on the other side. The plates are connected to the pipes and consequently they also increase the heat absorbing surface of the pipes. These plates are not necessary and may be dispensed with if desired.

A satisfactory refrigeration machine for household use is called upon to perform two distinct functions, i. e., the preservation of food and the making of ice for table use. The preservation of food is accomplished by keeping the temperature as nearly constant as possible and from 35° F. to 45° F. an aver-

age of, say, 40° F. If the temperature reaches as low a point as 32° F. , the food will be frozen. If it exceeds much above 45° F. , bacterial growth starts and the food decomposes. On the other hand in order to freeze water into ice, the temperature must be at 32° F. or lower. To accomplish the same efficiently and rapidly, the temperature should be from 10° F. to 20° F. , or an average of, say, 15° F. The problem, therefore, is to produce a temperature of say, 15° F. in the ice trays located in the evaporator and, say, 40° F. in the food compartment.

It is possible to maintain the temperature of the brine about the ice trays at the desired 15° F. and to so proportion the openings 8 and 6 into and out of the chamber 2 so that with a given temperature of the room in which the entire device is placed the air will circulate just fast enough to convey sufficient heated air from the food compartment 3 to the brine tank 9 and to return an equivalent amount of cold air through the opening 6 to the food compartment 4 and thence to the beginning thereby producing the proper temperature in the food compartment, but it will be evident that should the room temperature increase the air circulation within the structure must be correspondingly increased, and if the room temperature decreases, the air circulation must be correspondingly decreased, otherwise, notwithstanding a constant temperature of the brine and of the chamber 2, the temperature of the food will vary. This unstable condition has been a source of great difficulty in domestic mechanical refrigerators heretofore. To obviate this difficulty I have divorced the two functions and made them independent. I operate my system so that the temperature about the freezing drawers or trays 17' will always be sufficiently low to properly freeze water and other substances as desired. I then place in the opening 6 a damper or valve 15 so arranged that it will restrict the circulation through said opening always allowing just enough cold air from the compartment 2 to circulate through the compartments 3 and 4 to keep them at the desired uniform temperature independent of the room temperature in which the entire device is placed.

The operation of the valve or damper 15 is entirely automatic and is dependent upon the temperature surrounding the bulb 28 located within the food compartment and communicating with the bellows which operates the damper as heretofore described.

In order for a device of this nature to operate at its maximum efficiency the vapor on the suction side should be "dry". Whenever the suction vapor is accompanied with more or less liquid, evaporation takes place in the suction line and in the crankcase of the compressor, producing refrigeration at

points where it is not desired and often where it will do a great deal of harm. In order to avoid this serious difficulty I provide a large storage space for dry vapor above the surface of the liquid refrigerant so that whenever the compressor starts the gas may be drawn therefrom without drawing liquid refrigerant also.

When the motor stops running the refrigerant will continue to vaporize within the pipes 13 and 13' and within the header 11 and to accumulate in the storage space in the header until the pressure reaches that corresponding to the temperature of the liquid refrigerant in the header and pipe. This vaporized refrigerant in the storage space will be dry vapor. When the motor starts this dry vapor is drawn off into the suction pipe and the crankcase until the pressure is lowered sufficiently to start ebullition, after which the refrigerant boils quietly, delivering dry vapor into the storage space and thence into the suction pipe and crankcase.

The large chamber or header 11 provides not only a reservoir for dry gas but also for the liquid refrigerant so that there is always ample gas and liquid for the proper and efficient operation of the entire system.

The association of the relatively large chamber or header 11 with the damper 15 is considered a very important feature of my invention since the header acts as a reservoir both for the liquid and gaseous refrigerant and the damper prevents the undue vaporization of the liquid refrigerant. The liquid vaporizes and absorbs heat sufficient to keep the temperature about the freezing drawers or trays 17' at about 15 F. and the damper restricts the circulation of air through the opening 6 so that the temperature of the food compartments 3 and 4 cannot drop below, say, 40° F. If the opening 6 were unrestricted by the damper the circulation of the air therethrough would be very much more rapid, the circulation of warm air through the opening 8 would be correspondingly increased and the vaporization within the header would be much more rapid in order to maintain the desired temperature about the freezing trays. Thus the damper prevents undue lowering of the temperature in the food compartment and thereby conserves the vaporization of the liquid within the header, which, in turn, reduces the necessary operation of the compressor to supply further liquid to the header, thereby conserving electric power required to operate the entire system.

In refrigeration systems for household use it has been found very difficult to produce a sufficiently low temperature to satisfactorily freeze water or other substances. It is customary to provide trays for the reception of water and to locate these trays within sleeves or chambers surrounded by brine, the brine

being chilled by the vaporization of liquid refrigerant supplied to pipes arranged in the brine about the sleeves or chambers. The vaporization pipes heretofore employed have been long and tortuous, often in the form of coils of many turns whereby when the gas is liberated by ebullition it is obliged to make its way to the suction pipe through a long passage filled with liquid. This not only produces excessive resistance to the flow of gas, or "back pressure", and reduces ebullition, but it causes the liquid to boil very irregularly and often to boil over into the suction pipe and into the crankcase as heretofore described. In my present invention I employ the header 11, already described, to prevent the boiling over of the liquid refrigerant, and I further employ a series of simple U shaped pipes 13 and 13' attached to the header and extending downwardly and around the chamber 16 containing the freezing drawers. I employ a large number of independent pipes and by making them of very simple form with few turns I liberate the gas in large quantities and allow it to flow freely without back pressure into the header 11 where it gathers in the storage space as dry vapor. It has been found in practice that this form of vaporizer, consisting of a header with a large space for the storage of dry vapor and a series of U shaped evaporating tubes connected thereto, is very highly efficient and that it overcomes much of the difficulty heretofore experienced in the art.

The compressor unit consisting of the motor 30, compressor 31, and condenser 32 may be of any suitable type as for example that disclosed in Patent No. 1,286,612, granted to Bechtold and Mellowes, Aug. 20, 1918, and requires no further description.

The refrigerant after being condensed in the condenser 32 settles in the pocket 33 and is thence forced past the expansion valve, not shown, through the pipe 34, the tube 12 and pipe 13, 13' into the header 11 partially filling the same as indicated by the line 36 in Fig. 2. The charge of refrigerant and arrangement of parts is such that the header 11 is constantly maintained partially filled with refrigerant liquid. In other words, as fast as the refrigerant vapor which forms in all the above mentioned pipes and header is drawn through the return pipe 37, by the compressor when it is operating, liquid refrigerant is forced from the condenser up into the header and tubes to take its place and to thereby maintain approximately a constant amount of liquid refrigerant within the header.

The motor employed is one that is suitable for the motive power available. The motor shown is an electric one, and is controlled by any suitable thermally operated switch controlled mechanism. One form of switch controller mechanism for this purpose is shown diagrammatically in Fig. 2. A bulb 55 par-

tially filled with a liquid that vaporizes at low temperature, as for example, methyl chloride, is located in the brine tank 9 (see Fig. 2). A tube 56 connects this bulb with a 5 corrugated longitudinally extensible member 57 called a bellows mounted on the base plate 58. Attached to the upper end of the bellows 57 is an arm 59 connected at its outer end by a link 60 to a projection on the base plate 58. The inner end of the arm 59 has a bearing 61 10 which is adapted to be engaged by a knife bearing 62 carried by the lever 63. On the upper side of the lever 63 and located inwardly of the knife bearing 62 is a knife bearing 64 which engages a corresponding bearing 65 15 carried by the top frame member 66. On the outer end of the lever 63 is adjustably mounted a weight 67. A weighted lever 68 is pivoted to the inner end of the arm 63 and has an extension 69 that engages beneath the arm 63 20 which permits its elevation but prevents its being lowered beyond the point where it aligns with the arm 63.

The switch proper as shown consists of the 25 two contact points 38 and 39 which are adapted to be bridged by the conductor plate 40 carried by the springs 41 which are attached to the projection 42 rigidly connected to or integral with the arm 43 which in turn is 30 pivoted to the post 44. The springs are employed to insure a sliding contact. The free end of the arm 43 is adapted to contact the upper side of the conductor plate 40 to firmly hold the same against the contact points when 35 the switch is closed. An arm 45 pivoted to the post 44 and extending in the opposite direction from the arm 43 has an extension 46 that is adapted to engage the extension 47 of the latch 48 to release the same as will presently appear. The latch 48 has an upwardly 40 extending member 49 extending through an opening in the arm 43 and terminating in a hook 50 that engages the arm 43 to limit its upward movement. A notch 51 is adapted to 45 engage the arm 43 and hold it in its lowered position. A spring 52 tends to hold the latch rearwardly. Two springs 53 connecting the two arms 43 and 45 are adapted to pass dead center to hold the arms either in raised or lowered position. A link 54 connects the arm 45 to the outer end of the weighted lever 68.

In operation, when the temperature in the brine tank rises the vapor pressure in the 55 thermostat increases and this acts to elongate the bellows 57 which through the mechanism described lifts the outer end of the lever 63 thus lowering its inner end and permitting the downward movement of the weighted lever 68 to thereby lower the link 54 and with 60 it the arm 45. When the arm 45 carries the springs 53 past dead center the springs will cause the conductor plate to "snap" against the contact points 38 and 39 of the line 38' to thus start the motor. When the temperature 65 within the brine tank is lowered suffi-

ciently the reverse operation takes place and stops the motor. But in the reverse operation the conductor plate 40 remains in lowered position until the extension 46 of the arm 45 comes in contact with the extension 47 to release the notch 51 from engagement with the arm 43. This arrangement provides an almost instantaneous breaking of the circuit and thus prevents arcing. It will thus be seen that the arrangement is such that the motor is caused to operate only when the temperature rises above a predetermined maximum and is automatically stopped when the temperature falls below a predetermined minimum. 70 75 80

Mechanism is also provided for automatically controlling the supply of water flowing through the condenser coils in the condensing chamber 32. This means is so arranged that when the pressure within the condenser exceeds a predetermined maximum the motor will be automatically stopped by this means and when the pressure falls below that point the device will be automatically restored to the control of the thermally operated device. 85 For the purpose of illustration one form of this device is diagrammatically shown in Fig. 2.

A pipe 70 has one end connected to the condenser 32 and its other end to the lower end of a bellows 71. An arm 72 is connected to the upper end of the bellows 71 and has its outer end connected by means of a link 73 to the base plate 58. The inner end engages a needle valve 73' that controls the valve opening 75. A spring 76 tends to open the valve. 90 95 100

On the upper side of the inner end of the arm 72 is a bearing 77 which is engaged by a knife bearing 78 carried by the lever 79. The lever 79 has a weight 80 adjustably mounted on its outer end and is pivotally connected at its inner end to an arm 81 suspended by a link 82 from the top member 66. The free end of the link 81 is bent laterally as at 83 to engage beneath the weighted lever 68 to open the switch when the pressure in the condenser becomes excessive, as will presently appear. On the upper side of the lever 79 and located inwardly of the knife bearing 78 is a knife bearing 84 which engages a complementary bearing 85 carried by the top member 66. 110 115 120

In operation, when the motor starts, the pressure rises in the condenser 32 and this is communicated to the bellows 71 through the pipe 70, which elevates the arm 72 and thus permits the spring 76 to open the valve 75 which permits water from some suitable source of supply to enter through the pipe 86. The water is forced through the valve 75 and pipe 87 on into the condenser 32. After passing through the condenser coils, not shown, it is discharged through the pipe 88. 125

As the pressure increases the valve opens 130

wider to permit more water to flow through the condensing coils. If, however, the pressure exceeds a predetermined amount, as when the water has been cut off, the extension 5 of the bellows which causes the outer end of the arm 81 to move downwardly will cause the lateral extension 83 on the inner end of said arm to engage beneath the weighted lever 68 and elevate the same to thereby open the 10 switch and stop the motor. When the pressure is relieved the device will be automatically restored to the control of the thermally operated device.

It will be understood that various changes 15 may be resorted to in the form, construction, composition and arrangement of the several parts without departing from the spirit and scope of my invention; hence I do not wish to limit myself strictly to the structure herein 20 set forth.

What I claim is:

1. In combination, a brine tank provided with a recess as for the reception of an ice 25 pan, and a multiple path refrigerating duct disposed within said tank with each path about only one side of said recess and extending progressively in the same vertical direction from an inlet at one extremity of said duct to a junction with return duct means at 30 the other extremity thereof.

2. In combination, a brine tank provided with a recess extending therethrough as for the reception of an ice pan and extending into 35 said tank from a lateral face thereof, and a plurality of refrigerant duct means disposed within said tank each about a different part of said recess and each extending progressively in the same vertical direction from an inlet at one extremity of said duct to a junction with return duct means at the other extremity thereof.

3. In combination, a brine tank provided with a recess as for the reception of an ice 45 pan and extending into said tank from a lateral face thereof, and a plurality of refrigerant duct means disposed within said tank each about a different part of said recess and each extending progressively in the same vertical direction from an inlet at one extremity of said duct to a junction with return duct means at the other extremity thereof.

4. A refrigerant evaporating unit comprising a pair of elongated and horizontally disposed refrigerant vessels arranged one above 55 the other in substantially parallel relation; a pair of groups of refrigerant distributing ducts connected between the vessels, each of such groups of ducts being connected to the upper header longitudinally thereof and projecting in substantially opposite directions outwardly therefrom, thence downwardly in continuous substantially parallel vertical planes, and thence inwardly adjacent the opposite ends of the ducts, said ends there 60 communicating with the lower vessel longi-

tudinally of the latter, and a freezing tray disposed in the region between the groups of ducts for exchanging heat therewith.

5. A refrigerant evaporating unit comprising elongated and horizontally disposed refrigerant distributing means arranged in different horizontal planes in substantially parallel relation, a pair of groups of refrigerant distributing ducts connected between the upper and lower means, each of such groups of ducts being connected to the upper means longitudinally thereof and projecting downwardly in continuous substantially parallel vertical planes thence inwardly adjacent the opposite ends of the ducts, said ends there 70 communicating with the lower means longitudinally of the latter, and a freezing tray disposed in the region between the groups of ducts for exchanging heat therewith.

In testimony whereof I affix my signature. 85
